[57] **CLAIM**

The ornamental design for an earphone combined with microphone, as shown and described.

DESCRIPTION

FIG. 1 is a perspective view of an earphone combined with microphone showing my new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a rear elevational view thereof;

FIG. 7 is a bottom plan view thereof; and,

FIG. 8 is a view of the earphone in use wherein the person having the earphone is shown in broken lines for illustrative purposes only and forms no part of the claimed design.
